UNITED STATES PATENT OFFICE.

FRANK M. CURRAN AND CHARLES B. NORRIS, OF GRAND RAPIDS, MICHIGAN, ASSIGNEES TO HASKELITE MANUFACTURING CORPORATION, A CORPORATION OF NEW YORK.

SECURING MECHANISM FOR DOORS.

Application filed March 31, 1926. Serial No. 98,677.

The present invention has for its object to produce a simple and novel mechanism for clamping a door against a surrounding frame or the like with great pressure so as to insure a substantial hermetic sealing of the joint, without making the operation of such mechanism difficult for a person desiring to open or close the door.

The various features of novelty whereby our invention is characterized will herein-after be pointed out with particularity in the claims: but, for a full understanding of our invention and of its objects and advantages, reference may be had to the following detailed description taken in connection with the accompanying drawings, wherein:

Figure 1 is a front view of a clothes vault or safe equipped with securing mechanism constructed in accordance with the present invention, portions of the vault or safe being broken out; Fig. 2 is a view on an enlarged scale of the inside of the vault or safe in the vicinity of the securing mechanism, the securing mechanism being in its release position; Fig. 3 is a view similar to Fig. 2, showing the mechanism in its securing position the upper and lower portions of the structure to which the mechanism is applied being broken away; Fig. 4 is a side elevation of the actuating cam, viewed from the opposite side of that appearing in Fig. 3; Fig. 5 is a section taken on line 5—5 of Fig. 4; Fig. 6 is a section taken on line 6—6 of Fig. 2 and Fig. 7 is a section taken on line 7—7 of Fig. 3.

Referring to the drawings, 1 represents the wall of a vault or other structure having an opening adapted to be closed by a door 2 that is shown as being supported adjacent to one of its long edges by hinges 3. As best shown in Figs. 6 and 7, the wall and the door are shaped so as to have overlapping flanges 4 and 5, one of these flanges carrying a compressible gasket 6 which will seal the joint between the door and the wall when sufficient pressure is applied after the door is closed. The securing mechanism comprises a vertical shaft 7 rotatably mounted on the inner side of the door near the free long edge. On this shaft are a plurality of dogs 8 which, in one angular position of the shaft as shown in Fig. 7, engage with the inner side of the wall 1 adjacent to the door opening; whereas, in another angular position of the shaft, as shown in Fig. 6,

the dogs lie a sufficient distance inwardly from the edge of the door to pass through the door opening when the door is opened. In the particular arrangement shown, there are three clamping dogs, one at the top, one 60 at the bottom, and another midway between the top and bottom. This latter dog has an extension 10 on the rear thereof; this extension terminating in two lugs 11 and 12 spaced apart from each other. On the lug 12 is 65 a roller 13 of such a diameter as to leave a gap or space between it and the lug 11. An operating shaft 14 for the securing mechanism extends through the door in the same horizontal plane as the central securing lug, 70 and on the inner side of this lug and the shaft 7. On the outer end of the operating shaft is a handle 15 of any usual or suitable construction. The handle shown is of the type that is loose on the shaft so as normally to be freely rotated thereon; there being a securing means 16 by means of which the handle may be secured to the shaft so as to permit the operating shaft to be rotated thereby. On the operating shaft, on the 75 inner side of the door, is a cam device 17. This cam device has a peripheral flange 18 extending in a spiral direction around the operating shaft; the radial distance of the flange from the axis of the operating shaft 80 increasing from one end of the flange to the other, and one end of the flange being spaced lengthwise of the operating shaft a considerable distance from the other end. The flange is so shaped and the parts are so positioned with respect to each other, that the flange enters the notch or space between the lug 11 and the roller 13. Therefore, as the operating shaft is turned in one direction, the flange acts on the roller 13 and swings the shaft 7 in the counterclockwise direction as viewed in Figs. 6 and 7; whereas, when the operating shaft is turned in the other direction, the cam flange engages with the lug 11 and swings the shaft 7 in the clockwise direction. In other words, when the operating shaft is turned in one direction, it swings the dogs into holding position and, when turned in the other direction, it swings the dogs back into release position. In 105 swinging the dogs to the release position very little energy is required, and therefore the cam flange may be allowed to engage directly with the lug 11 without the intervention of an anti-friction device. 110

However, during the final securing movement of the dogs, when the door is closed, great pressure is applied in order to draw the door inwardly and compress the packing, and the anti-friction roller 13 has been provided to reduce the friction between the cam and the dog which it directly actuates.

It will be seen that the angle of the cam flange is not uniform. That portion of the 10 cam that engages with the anti-friction roller as the dogs approach their holding position and afterwards, being arranged at approximately right angles to the long axis 15 of the operating shaft; whereas the other end of the cam flange makes a considerable angle with such axis. The result is that the force applied to the operating handle is multiplied many times during the final securing 20 and clamping movements of the dogs, so that the dogs exert a very powerful clamping 25 action on the door. Upon the release of the dogs, their swinging movement is small during the first portion of the swinging movement of the operating handle but, when the dogs have been released, they are swung back quickly by that portion of the cam flange having the sharp pitch.

The portion of the cam flange of largest 30 radius is made more or less frusto-conical, as indicated at 19, whereby the cam is caused to engage with the cam roller across the entire thickness of the latter when the dogs are in securing position. Since the cam roller 35 swings through an angle of almost ninety degrees between the holding and release position, having its cylinder elements lying approximately parallel with the axis of the operating shaft in the first position and approximately at right angles to that axis in 40 the other position, the angle of the inclined face of the cam flange with respect to said axis must decrease from one end of the cam flange toward the other. Consequently the cam flange may be said to have a varying 45 pitch, a varying radius and a working face of varying inclination.

We claim:

1. The combination with a door adapted 50 to close in overlapping contact with a member beside the opening the door is designed to close, of a dog mounted on the inner side of the door so as to be capable of swinging

between a release position behind the door and a clamping position in engagement with the inner side of said member, said dog having a groove therein, operating shaft extending through the door at right angles to the axis about which the dog swings, and a cam of varying radius and varying pitch secured on the inner end of the shaft and 60 engaged in the groove of said dog.

2. The combination with a door, of a dog mounted on the inner side of the door so as to be capable of swinging from a release position behind the door to a locking position in which it projects beyond an edge 65 of the door, said dog having a groove therein, an operating shaft extending through the door, a cam on the inner end of the shaft engaged in the groove in said dog to swing 70 the dog, the pitch of the cam throughout that part thereof that engages the dog while the latter is in the vicinity of its locking position being small compared with the pitch at other points.

3. The combination with a door, of a dog mounted on the inner side of the door so as to be capable of swinging about an axis parallel with an edge of the door between a position in which it lies behind the door and 80 a position in which it projects beyond said edge, said dog having a groove bounded on one side by an antifriction roller, an operating shaft extending through the door at right angles to said axis, and a cam on said 85 shaft and extending into said groove.

4. The combination with a door, of a dog mounted on the inner side of the door so as to be capable of swinging about an axis parallel with an edge of the door between a position in which it lies behind the door and a position in which it projects beyond said edge, said dog having a groove bounded on one side by an antifriction roller, an operating shaft extending through the door at 90 right angles to said axis, and a cam on said shaft and extending into said groove, said cam being of varying radius and of varying 95 pitch.

In testimony whereof, we sign this specification.

FRANK M. CURRAN.
CHARLES B. NORRIS.
